UNITED STATES PATENT OFFICE.

LESTER KYLE ALDRICH, OF SIDNEY, OHIO.

CONVERTIBLE OSCILLATING ROTARY FEEDER.

Original application filed May 21, 1926, Serial No. 110,701. Divided and this application filed November 5, 1926. Serial No. 146,499.

The invention relates to a convertible oscillating rotary feeder and is a division of an application filed by me May 21, 1926, Serial No. 110,701 which contains claims generic to both arrangements, the claims of the present application relating to the construction and arrangement of the machine as a feeder of the continuous rotary type.

The object of the present invention is to improve the construction of automatic feeders for sheet material more especially that shown and described in Patent No. 1,546,184, granted to me July 14, 1925 and to provide a simple, practical and efficient automatic feeder of comparatively inexpensive construction capable of operating either as a rotary feeder or as an automatic feeder of the oscillating type with comparatively little change.

20 The oscillating type of feeder cannot be run faster than the machine to which it is attached and which it feeds as it is dependent on the mechanical movements of such machine for its operation. The rotary type 25 of automatic feeder can be run at variable speeds by simply varying the ratio of the driving mechanism. This type of feeder has the advantage over the oscillating type in feeding machines which do not require time, 30 such as buckle folders, perforating and ruling machines and with the shorter length of sheets the feeder can be speeded up to feed the sheets to the full capacity of the ruling machine or other machine to which the 35 sheets are fed.

Another object of the invention is to provide means to thoroughly wind the sheet before attempting to pull it off the stack or pile and also to equip the feeding machine 40 with means for controlling the vacuum separately on winding arms which lift and wind the sheet, and a pull off nozzle which carries the sheet from the stack or pile to the roll which completes the feeding operation 45 so that with light porous stock very little vacuum may be used in picking up the sheet and an additional vacuum may be employed to pull the sheet off the pile after the sheet has been picked up and wended.

50 The combination feeder makes it possible to provide a feeder that can be attached to any type of machine requiring an automatic feeder.

With these and other objects in view, the 55 invention consists in the construction and

novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a side elevation of a combination automatic feeder constructed in accordance with this invention and shown arranged as a feeder of the oscillating type.

Fig. 2 is a similar view of the opposite side of the machine.

Fig. 3 is a plan view of the same.

Fig. 4 is an enlarged detail longitudinal sectional view of the upper portion of the machine illustrating the arrangement of the winding arms and the pull off nozzle and the cam mechanism for controlling the operation of the same.

Fig. 5 is an enlarged plan view of a portion of the machine.

Fig. 6 is an enlarged detail sectional view of the air valve.

Fig. 7 is a detail view of one of the pepper box dials or disks for regulating the vent 85 passages.

Fig. 8 is a detail side view of the pull off nozzle.

Fig. 9 is an edge view of the same.

Fig. 10 is a detail view of one of the winding arms.

Fig. 11 is a side elevation showing the machine arranged as an automatic feeder of the rotary type.

Fig. 12 is a similar view showing the upper portion of the opposite side of the machine.

In the accompanying drawings in which is illustrated the preferred embodiment of the invention, the combination automatic feeder comprises in its construction a pull off nozzle 1 consisting of a disk adapted to be oscillated when the machine is arranged as a feeder of the oscillating type capable also of being continuously rotated to provide a feeder of the rotary type. The pull off nozzle is suitably fixed to a rotary shaft 2 journaled in suitable bearings in the sides of the frame 3 of the machine and provided at one portion of its periphery with an arcu-

ate series of suction mouths 4 for successively operating on the uppermost sheet 5 of a stack to pull the sheet off the stack and carry the same to a pull off roll 6 and rubber covered spools 7 which are arranged above the pull off roll and which cooperate with the same to complete the feeding operation and carry the sheet into the machine with which the automatic feeder is associated as clearly explained in the aforesaid patent. The suction mouths as explained in the aforesaid patent are arranged at regular intervals and are connected by passages or ducts 8 with lateral ports 9 which are adapted to be brought successively into register with an outlet or aperture of an air passage 10 carried by an air arm 11. The pull off nozzle is also provided with a curved slot 12 arranged concentric or in circular alignment with the arcuate series of ports 9 and adapted to be brought into register with the outlet of the passage 10 for destroying the vacuum during a portion of the revolution of the pull off nozzle when the machine is continuously rotating and operating as a rotary feeder. One end of the curved slot is spaced from the arcuate series of ports to provide an intervening imperforate surface 13 which is adapted to close or cover the outlet of the passage 10 during a portion of the movement of the pull off nozzle while the machine is operating both as a feeder of the rotary type and as a feeder of the oscillating type to cut off the suction from the nozzle and throw the full suction on one or more winding arms 14 which first engage the uppermost sheet 5 of the stack and then lift the same and move the edge of the sheet backwardly as illustrated in dotted lines in Fig. 4 of the drawings to produce an undulation in the sheet for winding the same in the manner explained in the aforesaid patent and similar to a pressman when winding a sheet by hand. During this winding operation the sheet is lifted and moved from the position illustrated in full lines in Fig. 4 of the drawing to that shown in dotted lines. The pivotal axis of the winding arms as herein-after fully explained is located a considerable distance above the stack of the sheets to cause the winding arms in their upward movement to move backward simultaneously approximately five-eighths of an inch which is ample to effect the operation of winding the sheet and separating the uppermost sheet from the stack. The winding arms also cooperate with means for discharging compressed air against the stack as fully explained in the aforesaid patent.

60 The winding arms 11 are suitably mounted on a transverse pivot shaft 15 mounted in suitable bearings in the sides of the frame 3 of the machine and carrying a cam actuated lever arm 16 and a valve operating arm 17. The winding arm 14 is approxi-

mately L-shaped and is secured at one end to the transverse pivot shaft 15 and is provided with a hollow or tubular portion 18 arranged approximately at a right angle to the portion which is attached to the pivot shaft. The hollow or tubular portion 18 which forms a passage for the air extends downwardly and provides at its lower end a suction mouth which is adapted to engage the uppermost sheet of the stack at the forward edge thereof and lift the same as before explained. The winding arm is inferiorly threaded at the upper end of the passage 19 for the reception of a threaded nipple 20 which forms a hose connection for connecting a flexible hose 21 to each of the winding arms.

The cam actuated lever arm 16 which is located at one side of the machine adjacent to the frame is provided at its outer or cam engaged end with a roll 22 which is mounted on a suitable journal 23 and which bears upon a rotary cam 24. The journal is preferably in the form of a screw threaded into the arm 16 as indicated at 24' in Fig. 5 of the drawings and the roll rests upon the cam 24 at the center of the top thereof as clearly illustrated in Fig. 4 of the drawings and as the winding arms 14 and the arms 16 and 17 are rigidly secured to the pivot shaft 15 by screws or other suitable fastening devices there is sufficient weight to cause the roll to press firmly against the cam and move the cam-actuated lever arm in accordance with the contour thereof. The cam is provided with a cut out portion or recess 25 forming a cam face for actuating the arm 16 for raising and lowering the winding arms to carry the same to the stack and to lift the uppermost sheet thereof and wind the same. The remaining portion of the peripheral surface of the cam is circular and maintains the winding arm in an elevated position while the pull off nozzle is operated to pull off the sheet and carry the same to the pull off roll and the rubber covered spools.

The arm 17 which operates the air valve is located exteriorly of the frame of the machine at the opposite side of that at which the cam actuated lever arm 16 is arranged and it is approximately L-shaped and extends downwardly from the pivot shaft 15 and longitudinally of the side of the machine to a point adjacent an air valve 26 provided with a cut off piston or movable valve member 27. The air valve consists of a body provided with a main longitudinal passage 28 and a smaller longitudinal passage 29. The valve is preferably arranged in a vertical position as shown and the passages 28 and 29 are vertical. The lower end of the vertical longitudinal passage 28 is connected with a main suction hose 30 by a nipple or hose connection 31 which is

threaded into the lower end of the passage 28 and a suitable hose connection or nipple 32 is threaded into the upper end of the main longitudinal passage 28 and for the attachment of a hose 33 which is connected with the suction nozzle 1 through the passage of the air arm 11. The smaller longitudinal passage 29 has threaded into its upper end a nipple or hose connection 34 which receives a hose 35 extending to one of the winding arms. The hose 36 extends to the other winding arm and is connected by an L-shaped nipple or hose connector 37 which is threaded at one end into a transverse passage or bore 38 extending into the body of the air valve from one face thereof and intersecting the longitudinal passages 28 and 29. The transverse air passage 38 communicates with the longitudinal passage 29 and also with the main longitudinal passage 28. When the suction is on the winding arms through the transverse passage 38 the suction is cut off from the pull off nozzle by the imperforate surface between the arms 25 cuate series of ports 9 and the curved slot 12 so that the entire suction will be on the winding arms. The suction which may be made either light or heavy to suit the character of the stock being fed by the machine 30 is regulated by means of pepper box dials 39 and 40 consisting of disks each provided with a plurality of apertures 41 of different sizes adapted to be brought into register respectively with transverse vent passages 35 42 and 43 extending from the exterior to the longitudinal passages 28 and 29 as clearly shown in Fig. 6 of the drawings. Each pepper box dial is mounted on a pivot 44 consisting of a screw which passes through 40 a central opening 45 in the perforated disk which has disposed on it a coiled spring 46 which is interposed between the head of the screw and the outer face of the disk for pressing the same against the body of the 45 air valve. The body of the air valve is provided at the vents 42 and 43 with smooth flat circular faces 47 and 48 to receive the disks which constitute the pepper box dials. The disks are adapted to be rotated to bring 50 any one of its openings into register with the vent passages 42 and 43.

The cut off piston or movable valve member 27 which is cylindrical is mounted in the lower portion of the bore or passage 29 and it is movable from the position illustrated in full lines in Fig. 6 of the drawings to the dotted line 49 in the said figure to close the passages leading to the winding arms for cutting off the vacuum from the winding arms to throw the full force of the vacuum into the hose extending from the main longitudinal passage of the air valve to the pull off nozzle. The cut off piston is reciprocated in the valve chamber passage 29 of 55 the air valve by the arm 17.

The air arm is provided with a smooth flat bearing surface to fit against the pull off nozzle and this surface is preferably formed by a wood bushing 50 saturated with oil to form a suction contact member but any other suitable construction may of course be employed. The bushing 50 is mounted in a metal sleeve 51 carrying a nipple or hose connection 52 to which is connected the hose 33 extending from the nipple 32 of the air 70 valve to the air arm. The sleeve 51 provided with a stem 53 and a coiled spring 54 is arranged on the stem at a recess 55 in the end of the bearing arm and is interposed between one wall of the recess and the bearing sleeve for yieldably maintaining the wood bushing in contact with the pull off nozzle. The construction of the wood nozzle and the spring actuated sleeve is substantially the same as that shown and described 80 and claimed in an application filed by me February 23, 1926, Serial No. 89,875. The air arm 11 is fixed by a screw or other suitable fastening device to a transverse rod or shaft 56 on which are mounted the arms 57 which carry the rubber covered spools 7 which cooperate with the pull off roll 6. The rubber covered spools are constructed and arranged substantially as shown and described in the aforesaid patent. 95

The approximately L-shaped valve operating arm 17 is connected to the lower end of the cut off piston by a pin or pivot 58 and it is provided adjacent to the pin or pivot 58 with a laterally extending pin 59 arranged 100 to operate a pivoted valve 60 mounted on the exterior of the valve body and arranged to cover and uncover a port or opening 61 in the air valve. The pivoted valve member 60 consists of a plate having angularly related portions and mounted at its angle on a pivot 62 preferably consisting of a screw as shown and provided at its outer end with a head and having a coiled spring 63 interposed between the head of the screw and the 105 movable valve member for creating the necessary pressure to maintain the desired contact between the pivoted valve member and the valve body. One arm or portion of the movable valve body is arranged to cover and uncover the said port or opening 61 and it slides or swings to and from its closed position and its other arm is connected with a crank disk or wheel 63 by means of a link 64 pivoted at one end to the crank member 110 or wheel by a wrist pin 65 and provided with a longitudinal slot 66 receiving a pin or pivot 67 mounted on one end of the movable valve member 60. The pin or pivot 67 operates in the slot and the crank element 115 120 63 is adapted through the rotation of the cam shaft 2 to move the valve member 60 to its open position for destroying the vacuum and the laterally extending pin of the arm 17 is adapted to engage the movable valve 125 130

member for actuating the same to move the valve member to its closed position for restoring the vacuum as the arm 17 and the cam-actuated lever arm arrive at their lowest position to provide the necessary vacuum for the winding arms as the latter are lowered to come in contact with the uppermost sheet of the stack. When the laterally extending pin 59 of the arm 17 actuates the pivoted valve member 60 the connecting pin 67 thereof occupies the position in the upper portion of the slot 66 due to the rotation of the crank element 63 and the slot permits the operation of the pivoted valve member 10 by the laterally extending pin of the arm 17. The air valve is also provided with a throttle valve consisting of a port or opening 68 and a pivoted hand operated valve lever 69 pivoted intermediate of its ends on a pin or screw 70 and maintained in proper frictional contact with the valve body by a coiled spring 71. The valve lever 69 is adapted to be operated by hand to cover and uncover the port or opening 68 for destroying and 20 restoring the vacuum so that the feeding of the machine may be stopped and started as required.

The main suction hose 30 is connected with a rotary vacuum pump 72 and the pull off nozzle is reversely rotated or oscillated by means of a pinion 73 mounted on a cam shaft and meshing with a rack 74 arranged at the upper end of a vertically reciprocating bar 75 extending to the lower portion of the machine and connected at its lower end by a suitable pivot with a crank arm 76 of a transverse crank shaft 77 journalled in suitable bearings of the frame of the machine and provided at the opposite side 30 thereof with an upwardly extending crank arm 78 designed to be connected with the mechanism of the press or other machine to be fed by the automatic feeder so that the automatic feeder will operate in conjunction 40 with the said press or other machine and at the speed thereof. The crank arm 76 extends approximately in a horizontal direction from the shaft 77 and is moved upwardly and downwardly to reciprocate the rack bar 75 when the arm 78 is oscillated by the press or other machine.

The stack of sheets is arranged upon a vertically movable table 79 constructed substantially the same as that shown in the aforesaid patent with the exception that the mechanism for elevating the table automatically is operated by an elevating lever 80 fulcrumed intermediate of its ends at 81 and pivotally connected at one end with the rack 50 bar and at the other end with the vertically movable bar 82 of the ratchet mechanism. When the machine is arranged as an oscillating feeder as illustrated in Fig. 1 of the drawings the elevating mechanism and the feeding mechanism are actuated by the

printing press bed lever or the mechanism of any other machine to which the feeder is attached. The link or bar 82 corresponds with the slotted link of the ratchet mechanism of the aforesaid patent and as the particular construction of the ratchet mechanism and the means for mounting and transmitting motion to the vertically movable table 79 are substantially the same as that shown and described in the aforesaid patent, a detail description and illustration of such mechanism in the present application is deemed unnecessary.

The rotary suction fan 72 is driven by an electric motor 83 which is connected with the rotary suction pump by a belt 84 and pulleys 85 and 86 but any other suitable means may of course be employed for transmitting motion from the electric motor to the rotary suction fan which as explained in the aforesaid patent discharges into a tank 87 which supplies the compressed air for discharging upon the stack as fully explained in the said patent.

The stack of sheets is arranged on the table between abutments 88 and 89 and as the suction nozzle rotates in the opposite direction to the arrow in Fig. 4 of the drawings the imperforate or dead surface 13 closes the opening in the wood bushing of 95 the air arm as the rotary suction disk nears the limit of its backward movement the cam has lowered the cam actuated lever which is attached to the pivot shaft carrying the winding arms and the cut off piston arm 17. As the cut off piston arm moved downwardly the pin 59 projecting laterally from the said arm 17 closed the valve 60 covering the exhaust port 61 restoring the full suction on the valve. The outlet or port at the wood bushing is closed by the imperforate or dead surface when the suction is on the winding arms. The direction of the rotation of the suction nozzle is now reversed and the suction nozzle moves in the opposite direction, lifting the winding arms which move in a backward direction as they rise to the level of the bottom of the rotary suction nozzle. When the winding arms have moved upwardly to this point the cut off piston arm 115 17 is also lifted, raising the cut off piston to the dotted line position shown in Fig. 6. The suction nozzle which has been rotating with the cam has arrived at the position where just as the piston cuts off the suction 120 from the winding arms the first port of the arcuate series has come into register with the port or opening in the wood bushing, putting all of the suction on the hose extending from the valve to the suction 125 nozzle. As the suction nozzle rotates it pulls the sheet from the pile and the sheet passes between the pull off roll and the rubber covered spools. As the suction nozzle reaches the limit of its forward rotation the 130

eccentric element or disk 63 has pulled upon the valve 60 and uncovered the exhaust port 61 thereby rendering the suction ports inactive on the nozzle as the same rotates backwardly. Also the winding arms are inactive when descending until almost the limit of the downward movement when the said laterally projecting pin 59 closes the valve 60 and restores the vacuum when the winding arms are in position to pick up the next sheet.

To convert the oscillating or reversely rotating feeder into a continuously rotating feeder the slotted link or connection 64 is removed and the valve 60 is closed. The pinion 73 and the rack bar 75 are then removed and the pinion is replaced by a pulley 88' or other rotary element and the elevating lever 80 is connected by a link or connecting rod 89' with a wrist pin 90. The pulley 88' is designed to be operated by a belt but sprocket gearing may of course be employed and the rotation of the sprocket wheel 88 will continuously rotate the suction nozzle or disk in the direction of the arrow in Fig. 4 of the drawings. No change is made in the cut off piston lever 17.

Referring to Fig. 4 of the drawings which shows the winding arms down ready to pick up the sheet, when the cam is in this position the arm 17 has caused the cut off piston to descend and the vacuum is on the winding arms owing to the fact that the rotary suction disk or nozzle has rotated beyond the end of the curved slot and the imperforate or dead surface 13 closes the outlet or port of the wood bushing. As the winding arms lift the sheet and wind it, the cut off valve closes cutting off the suction from the winding arms and transmitting it to the rotary suction nozzle as the first port has rotated into register with the port or outlet of the wood bushing and the sheet is now pulled off the pile by the rotary movement of the suction disk or nozzle and the successive engagement of the suction mouths with the sheets. As the suction disk or nozzle continues to rotate the curved slot 12 comes into register with the port or opening of the wood bushing thereby destroying the vacuum on the air valve and the suction nozzle and winding arms. The rotary suction nozzle or disk continues its rotary movement and the rotation of the cam lowers the winding arms and when they are just at their lowest point the curved slot passes beyond the port or opening of the wood bushing and the vacuum is restored ready to pick up the next sheet. The backward movement caused by the arrangement of the pivot shaft with relation to the stack of sheets produces an undulatory and winding action upon the sheet as the winding arm raises it thereby separating it from the stack

and enabling it to be pulled off the same by the operation of the rotary suction nozzle or disk. Any suitable means may be employed for rotating the pull off roll and also the rotary element 88 for imparting a continuous rotary movement to the pull off nozzle. 70

What is claimed is:

1. A feeder of the class described including a pull off suction nozzle mounted for rotary movement on a fixed axis and located above and in spaced relation to a stack 75 of sheets, means for continuously rotating the nozzle, and oscillating means consisting of a pivoted suction arm for picking up a sheet and moving the same backward for forming an undulation in the picked up 80 sheet and for delivering the sheet to the pull off nozzle.

2. A feeder of the class described including a suction nozzle mounted on a fixed axis for rotary movement above and in spaced 85 relation with a stack of sheets for advancing a sheet to pull the same from the stack, means for continuously rotating the nozzle, oscillating means for picking up a sheet and lifting the same to deliver it to the rotary 90 suction nozzle, and separate means for varying the amount of suction on the oscillating means.

3. A feeder of the class described including a pull off nozzle mounted for rotary 95 movement on a fixed axis and located above a stack of sheets and oscillating means for picking up a sheet and delivering the same to the pull off nozzle, means for continuously rotating the nozzle, said oscillating means 100 consisting of a pivoted suction arm being mounted for movement on a fixed axis located above the stack a sufficient distance to cause a backward movement of the picked up sheet to produce an undulation on the 105 picked up sheet to wind the same.

4. A feeder of the class described including a pull off suction nozzle consisting of a disk mounted for rotary movement on a fixed axis for continuous rotary movement 110 in one direction, means for continuously rotating the nozzle, and an oscillating winding arm pivoted in advance of the pull off nozzle and arranged to pick up a sheet from a stack and move the picked up sheet backward to wind the same and deliver it to the pull off nozzle. 115

5. A feeder of the class described including a pull off suction nozzle mounted for rotary movement on a fixed axis, a cam rotating with the pull off nozzle, oscillating means for picking up a sheet from a stack and delivering it to the pull off nozzle, and an arm connected with the said means and actuated by the cam for oscillating the said 120 means. 125

6. A feeder of the class described including a pull off suction nozzle mounted for

- rotary movement on a fixed axis, a cam rotating with the pull off nozzle, an oscillating winding arm mounted for movement on a fixed axis to pick up a sheet from a stack 5 and wind the picked up sheet and deliver the same to the pull off nozzle, and a lever arm connected with the winding arm and engaged with and actuated by the cam.
7. A feeder of the class described including a rotary pull off suction nozzle, means for continuously rotating the nozzle, an oscillatory winding arm arranged to pick up a sheet from a stack and deliver the same to the pull off nozzle, an air valve having 10 passages connected with the winding arm and the pull off nozzle and adapted to open and close the passage to the winding arm, means for operating the air valve, and means for simultaneously controlling the suction on the pull off nozzle.
8. A feeder of the class described including a rotary suction nozzle mounted for rotary movement on a fixed axis, means for continuously rotating the nozzle, an oscillatory suction arm arranged to pick up a sheet from a stack and deliver it to the suction nozzle, a fixed air arm having a pull off passage extending to the suction nozzle, means carried by the nozzle for controlling the 15 suction passage of the air arm, an air valve for controlling the suction of the suction arm, and means for operating the air valve simultaneously with the suction arm.
9. A feeder of the class described including a pull off nozzle mounted for rotary movement on a fixed axis, a cam rotating with the pull off nozzle, a fixed air arm having a suction passage extending to the pull off nozzle, the latter being provided with 20 means for controlling the said suction passage, a pivoted shaft having a lever arm engaged with the cam, an oscillatory suction arm carried by the pivoted shaft and arranged to pick up a sheet from a stack and deliver it to the pull off nozzle, an air valve having 25 passages connected with the suction arm and the said air arm and provided with a movable valve member for opening and closing the passage to the suction arm, and an arm also mounted on the said pivoted shaft and connected with the movable member of the valve for actuating the same simultaneously with the oscillation of the suction arm.
10. A feeder of the class described including a rotary pull off nozzle, an oscillatory suction arm arranged to pick up a sheet and deliver it to the rotary pull off nozzle, a main suction tube, an air valve connected 30 with the main suction tube and having passages connected with the rotary pull off nozzle and with the oscillatory winding arm, said valve having a cut off piston arranged to open and close the passage to the suction 35 arm, and an oscillatory arm movable with the suction arm and connected with the cut off piston for reciprocating the same simultaneously with the oscillation of the suction arm, the rotary pull off nozzle being provided with a plurality of air ports adapted to be successively brought into communication with one of the passages of the said air valve and a portion of the nozzle being imperforate for cutting off the suction while the suction is on the winding arm. 75
11. A feeder of the class described including a suction pull off nozzle mounted for rotary movement on a fixed axis provided with a plurality of ports and having an imperforate dead surface adjacent to the said ports, an oscillating suction arm arranged to lift a sheet from a stack and deliver the same to the pull off nozzle, an air valve having 40 passages communicating with the suction arm and with the pull off nozzle, said air valve being provided with a movable member arranged to open and close the passage leading to the suction arm, the passage leading to the pull off nozzle being adapted by the rotation of the nozzle to be brought into communication with the said ports and to be closed by the imperforate dead surface, and means for operating the movable valve member for closing the suction to the winding arm when the said ports are in communication with the air valve and for opening the passage to the suction arm when the passage to the nozzle is closed by the imperforate surface thereof. 80
12. A feeder of the class described including a rotary pull off nozzle mounted for rotary movement on a fixed axis, a cam rotating with the said pull off nozzle, an oscillatory winding arm arranged to pick up a sheet from a stack and deliver it to the pull off nozzle, a lever arm connected with the winding arm and arranged to be actuated and controlled by the rotation of the cam, and means for imparting a continuous rotary movement to the cam and the pull off nozzle. 85
13. A feeder of the class described including a rotary pull off nozzle mounted for rotary movement on a fixed axis, a cam rotating with the said pull off nozzle, an oscillatory winding arm arranged to pick up a sheet from a stack and deliver it to the pull off nozzle, a lever arm connected with the winding arm and arranged to be actuated and controlled by the rotation of the cam, means for imparting a continuous rotary movement to the cam and the pull off nozzle, an air valve having 90 passages connected with the nozzle and the winding arm and provided with a movable valve member for opening and closing the passage to the winding arm, and an oscillating arm connected to the movable valve member and also with the 95
14. A feeder of the class described including a suction pull off nozzle mounted for rotary movement on a fixed axis, a cam rotating with the said pull off nozzle, an oscillatory winding arm arranged to lift a sheet from a stack and deliver the same to the pull off nozzle, an air valve having 100 passages communicating with the suction arm and with the pull off nozzle, said air valve being provided with a movable member arranged to open and close the passage leading to the suction arm, the passage leading to the pull off nozzle being adapted by the rotation of the nozzle to be brought into communication with the said ports and to be closed by the imperforate dead surface, and means for operating the movable valve member for closing the suction to the winding arm when the said ports are in communication with the air valve and for opening the passage to the suction arm when the passage to the nozzle is closed by the imperforate surface thereof. 105
15. A feeder of the class described including a suction pull off nozzle mounted for rotary movement on a fixed axis, a cam rotating with the said pull off nozzle, an oscillatory winding arm arranged to lift a sheet from a stack and deliver the same to the pull off nozzle, a lever arm connected with the winding arm and arranged to be actuated and controlled by the rotation of the cam, and means for imparting a continuous rotary movement to the cam and the pull off nozzle. 110
16. A feeder of the class described including a suction pull off nozzle mounted for rotary movement on a fixed axis, a cam rotating with the said pull off nozzle, an oscillatory winding arm arranged to lift a sheet from a stack and deliver the same to the pull off nozzle, a lever arm connected with the winding arm and arranged to be actuated and controlled by the rotation of the cam, means for imparting a continuous rotary movement to the cam and the pull off nozzle, an air valve having 115 passages connected with the nozzle and the winding arm and provided with a movable valve member for opening and closing the passage to the winding arm, and an oscillating arm connected to the movable valve member and also with the 120
17. A feeder of the class described including a suction pull off nozzle mounted for rotary movement on a fixed axis, a cam rotating with the said pull off nozzle, an oscillatory winding arm arranged to lift a sheet from a stack and deliver the same to the pull off nozzle, a lever arm connected with the winding arm and arranged to be actuated and controlled by the rotation of the cam, means for imparting a continuous rotary movement to the cam and the pull off nozzle, an air valve having 125 passages connected with the nozzle and the winding arm and provided with a movable valve member for opening and closing the passage to the winding arm, and an oscillating arm connected to the movable valve member and also with the

lever arm whereby the valve member and the winding arm are operated simultaneously.

14. A feeder of the class described including a rotary pull off nozzle mounted for rotary movement on a fixed axis, a cam rotating with the said pull off nozzle, an oscillatory winding arm arranged to pick up a sheet from a stack and deliver it to the pull off nozzle, a lever arm connected with the winding arm and arranged to be actuated and controlled by the rotation of the cam, a rotary element connected with the cam and the pull off nozzle for imparting a continuous rotary movement to the same, said rotary element having a wrist pin and an oscilla-

tory lever connected with and actuated by the wrist pin and adapted to impart movement to a table elevating mechanism.

15. A feeder of the class described including a suction nozzle mounted on a fixed axis for rotary movement above and in spaced relation with a stack of sheets for advancing a sheet to pull the same from the stack, means for continuously rotating the nozzle, oscillating means for picking up a sheet and lifting the same to deliver it to the rotary suction nozzle, and means for varying the amount of suction on the oscillating means independently of the nozzle.

In testimony whereof I affix my signature.
LESTER KYLE ALDRICH.
